CYLINDRICAL DISPENSING STAND FOR SERVICE FILLING STATIONS

Eliot F. Noyes, New Canaan, Ernest M. Bevilacqua, Wilton, and Allen D. Hawthorne, New Canaan, Conn., assignors to Mobil Oil Corporation, a corporation of New York

Filed Mar. 21, 1966, Ser. No. 1,576

Term of patent 14 years

(Cl. D52—2)

FIG. 1

FIG. 2

FIG. 3

FIG. 4

FIG. 1 is an elevational view of one side of a cylindrical dispensing stand for service filling stations, showing our new design.

FIG. 2 is a left hand side view of FIG. 1.

FIG. 3 is a view similar to FIG. 2, but showing the circular closure shield raised to the upper portion of the dispensing stand.

FIG. 4 is a right hand side view of FIG. 1.

The side opposite to the side disclosed in FIG. 1 is a mirror image of the side shown.

The dominant features of our design reside in the portions shown in full lines. The canned oil display shown in the broken lines is for illustrative purposes only.

We claim:

The ornamental design for a cylindrical dispensing stand for service filling stations, as shown and described.
